(57) CLAIM

The ornamental design for a cosmetic refrigerator, as shown and described.

DESCRIPTION

FIG. 1 is a front, left and top perspective view of a cosmetic refrigerator showing our new design;

FIG. 2 is a rear, right and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the cosmetic refrigerator taken from upper circle part in FIG. 5; and,

FIG. 10 is an enlarged view of the cosmetic refrigerator taken from lower circle part in FIG. 5.

The broken lines showing of the enlargement indicia in FIGS. 5, 9, and 10 is shown for the purpose of illustrating the bounds of the enlargement and forms no part of the claimed design.

The portions of the cosmetic refrigerator shown in broken lines form no part of the claimed design.

1 Claim, 10 Drawing Sheets
